UNITED STATES PATENT OFFICE.

HUBERT K. KRANTZ, OF WILKINSBURG, PENNSYLVANIA, ASSIGNOR TO WESTINGHOUSE ELECTRIC & MANUFACTURING COMPANY, A CORPORATION OF PENNSYLVANIA.

SWITCH MECHANISM.

Application filed June 10, 1922. Serial No. 567,322.

To all whom it may concern:

Be it known that I, HUBERT K. KRANTZ, a citizen of the United States, and a resident of Wilkinsburg, in the county of Allegheny and State of Pennsylvania, have invented a new and useful Improvement in Switch Mechanism, of which the following is a specification.

My invention relates to switch mechanisms and particularly to switch mechanisms of the safety enclosed type.

One object of my invention is to provide a switch mechanism of the enclosed safety type wherein the housing containing the switch and fuse mechanism is divided into separate compartments by a barrier, the switch mechanism being mounted in one compartment and the fuse mechanism in the other compartment, and wherein the door for the fuse compartment is provided with a latch so interlocked with the switch mechanism that it cannot be moved to released position so long as the switch is in closed position.

Another object of my invention is to provide a switch mechanism, having the above characteristics, wherein the door is provided with an interlocking member that is disposed between the switch mechanism and the latch for the door for preventing closing movement of the switch when the door is in open position.

Another object of my invention is to provide an interlocking mechanism for the door latch and switch that is simple in construction and inexpensive to manufacture.

A further object of my invention is to provide a safety enclosed switch mechanism wherein the bottom of the housing is provided with openings that are closed by perforate insulating plates through which the conductors extend.

These and other objects, that will be made apparent throughout the further description of my invention, are attained by means of the switch mechanism hereinafter described, and illustrated in the accompanying drawings, wherein:

Figure 1 is a front view of the switch mechanism;

Fig. 2 is a longitudinal section through the switch mechanism shown in Fig. 1, taken on the line II—II thereof;

Fig. 3 is a transverse section through the switch mechanism taken on the line III—III

of Fig. 2, showing a portion of the barrier broken away, and

Fig. 4 is a fragmental plan view of the interlock mechanism.

Referring to the drawings, the apparatus includes a metal housing 5 that is divided into a switch compartment 6 and a fuse compartment 7 by means of a barrier 8. The housing is provided with a detachable cover 9 upon which the switch brushes and operating mechanism therefor are mounted.

The switch, which is similar in construction to that illustrated in Patent No. 1,292,810, safety panel boxes, issued to H. F. Krantz January 28, 1919, comprises a bracket 11 upon which the switch brushes 12 are pivoted. The brushes are connected to an operating handle 13 by means of a pair of toggle links 14 and 15 that are adapted to be moved to open and to closed position by means of a cam plate 16 which has a lost-motion connection with the knee pivot of the toggle.

A plunger 17 is pivotally connected to the knee pivot of the toggle links and is adapted to slide longitudinally of the housing and to be moved toward the fuse compartment when the switch is moved to closed position.

A door 18 is hinged to the side of the housing by means of hinges 19 and serves to close the fuse compartment 7. A latch bar 21 is secured to the inner side of the door and extends longitudinally of the housing or parallel to the axes of the hinges 19. One end of the bar projects beneath a flange 22 and serves to retain the door in closed position. The latch bar is normally held in closed position by means of a helical spring 23 that is disposed between a bracket 24 on the door and a collar 25 on the latch bar 21.

The plunger 17 is provided with an extension 26 having an inwardly-turned wing 27 of less width than the extension. The extension operates through a notch 27^a cut in the outer edge of the barrier 8 and projects into the fuse compartment 7, as indicated in dotted lines in Fig. 4, when the switch is in closed position. By reason of this construction, it will be seen that, so long as the switch is in closed position, opening movement of the latch bar 21 is prevented by the wing 27. The latch bar 21 is provided with an operating handle 28.

The latch bar 21 serves to lock the side of the door adjacent to the end of the hous-

ing and it is, therefore, desirable to provide means for latching the opposite side of the door. For this purpose, a clip 29 is secured to the under side of the door and is provided 5 with an offset portion 31 which engages one corner of the extension 26 when the switch is in closed position.

In order to interlock the door with the switch so that the door cannot be opened 10 so long as the switch is in closed position, an interlocking bar 32 is pivoted to a bracket 33 that is secured to the inner side of the door 18. The bar is provided, at its free end, with a slot 33a in which a pin 34 fixed 15 to a bracket 35 extends. The bar is provided with a notch 36 aligned with the wing 27 which permits of movement thereof toward the latch bar 21. Slight opening movement of the door 18 causes the bar 32 20 to be moved across the path of movement of the wing 27 and prevents closing movement of the switch so long as the door is in other than closed position. The bar 32 also serves to limit the opening movement of the door. 25 The points at which the bar 32 is pivoted are so related with respect to the hinge of the door that the bar 32 lies across the path of movement of the extension 26 when the door is in any position between open and 30 closed positions.

In addition to the interlock features of the switch mechanism, the housing is provided with an improved means for supporting the conductors entering the housing.

35 The ends of the housing are provided with openings 37 and 38 that are closed by insulating plates 39 and 41, respectively. The plates are provided with perforations 42 through which the conductors 43, connected to the fuse and switch terminals, extend. This arrangement eliminates the necessity for having knockout openings in the ends of the housing and the bushings usually employed with such structures.

40 45 While I have described and illustrated but one embodiment of my invention, it will be apparent to those skilled in the art that various changes, modifications, substitutions, additions and omissions may be made 50 therein without departing from the spirit and scope of my invention, as set forth in the appended claims.

I claim as my invention:

55 1. Switch mechanism comprising a housing having an opening therein, a movable door for the housing, a switch member movable to open and to closed positions, a latch member for the door normally yieldingly retained in closed position, means on the 60 switch member for preventing opening movement of the latch member when the switch member is in closed position and means actuated by the door and movable between the said means and the latch member for precluding closing movement of the 65

switch so long as the door is in other than closed position.

2. Switch mechanism comprising a housing having an opening therein, a door for closing the opening hinged at one side of the 70 housing, a latch member carried by the door and movable longitudinally of the housing and engaging the housing for retaining the door in closed position, a switch member within the housing movable to open and to 75 closed positions, means actuated by the switch member movable longitudinally of the housing for preventing releasing movement of the latch member when the switch member is in closed position, and means movable by the door transversely of the housing for preventing closing movement of the switch member so long as the door is in other than closed position.

3. Switch mechanism comprising a housing having an opening therein, a door for closing the opening hinged at one side of the housing, a latch member carried by the door and movable longitudinally of the housing and engaging the housing for retaining the door in closed position, a switch member within the housing movable to open and to closed positions, means actuated by the switch member movable longitudinally of the housing for preventing releasing movement of the latch member when the switch member is in closed position, and an interlocking bar pivotally connected to the door and to the housing and movable across the path of movement of the said means for preventing closing movement of the switch so long as the door is in other than closed position.

4. Switch mechanism comprising a housing having an opening therein, a door for closing the opening hinged at one side of the housing, a latch member carried by the door and movable longitudinally of the housing and engaging the housing for retaining the door in closed position, a switch member within the housing movable to open and to closed positions, means actuated by the switch member movable longitudinally of the housing for preventing releasing movement of the latch member when the switch member is in closed position, and an interlocking bar pivotally connected to the door and to the housing and movable across the path of movement of the said means for preventing closing movement of the switch so long as the door is in open position.

5. Switch mechanism comprising a housing having an opening therein, a door for closing the opening hinged at one side of the housing, a latch member carried by the door and movable longitudinally of the housing and engaging the housing for retaining the door in closed position, a switch member within the housing movable to open

and to closed position, means actuated by the switch member movable longitudinally of the housing for preventing releasing movement of the latch member when the 5 switch member is in closed position, and an interlocking bar pivotally connected to the door and provided with a slot-and-pin connection to the housing and movable across the path of movement of the said means for 10 preventing closing movement of the switch so long as the door is in open position.

6. Switch mechanism comprising a housing having an opening therein, a door for closing the opening hinged at one side of 15 the housing, a latch member carried by the

door and movable longitudinally of the housing and engaging the housing for retaining the door in closed position, a switch member within the housing movable to open and to closed positions, means actuated by 20 the switch member movable longitudinally of the housing for engaging the door and supplementing the latch for preventing opening movement thereof when the switch is in closed position. 25

In testimony whereof, I have hereunto subscribed my name this 29th day of May, 1922.

HUBERT K. KRANTZ.
